MOLD JACKET

James F. Hines, Lakewood, Ohio, assignor, by
mesne assignments, to Hines Flask Company,
Cleveland, Ohio, a corporation of Ohio

Application April 10, 1951, Serial No. 14,784

Term of patent 14 years

(Cl. D54—8)

To all whom it may concern:

Be it known that I, James F. Hines, a citizen of the United States, residing in Lakewood, county of Cuyahoga, and State of Ohio, have invented a new, original, and ornamental Design for a Mold Jacket, of which the following is a specification, reference being had to the accompanying drawings, forming a part hereof.

Fig. 1 is a perspective view of a mold jacket embodying my new design; Fig. 2 is an elevation of any side of the jacket, Fig. 3 is a vertical cross section in the plane indicated by the line 3—3 on Fig. 1 looking toward the handle.

I claim:

The ornamental design for a mold jacket, as shown.

JAMES F. HINES.
